(57) **CLAIM**

The ornamental design for a firestopping bushing made from two separate identical parts, as shown.

DESCRIPTION

FIG. 1 is a front plan view of the bushing embodying our new design;
FIG. 2 is a front three-quarter perspective view of either of the two identically configured parts;
FIG. 3 is a front plan view and rear plan view;
FIG. 4 is a left side plan view and a right side plan view of the embodiment shown in FIG. 1;
FIG. 5 is a top plan view of the embodiment shown in FIG. 1; and,
FIG. 6 is a bottom plan view of the embodiment shown in FIG. 1.
